DESIGN FOR AN AUTOMATIC COFFEE URN OR SIMILAR ARTICLE

Donald F. Swanson, Chicago, Ill.

Application February 2, 1945, Serial No. 117,729

Term of patent 14 years

(Cl. D44—26)

To all whom it may concern:

Be it known that I, Donald F. Swanson, a citizen of the United States and residing in the city of Chicago, in the county of Cook and State of Illinois, have invented a new, original, and ornamental Design for Automatic Coffee Urns or Similar Article, of which the following is a specification, reference being had to the accompanying drawing, forming a part thereof.

On the drawing:

Fig. 1 is a front elevational view of a coffee urn showing my new design.

Fig. 2 is a side elevation thereof.

Fig. 3 is a top plan view of my coffee urn.

Fig. 4 is an enlarged detailed view of a front panel thereof.

I claim:

The ornamental design for an automatic coffee urn or similar article, substantially as shown.

DONALD F. SWANSON.
